US0D1062601S

(12) **United States Design Patent** (10) Patent No.: **US D1,062,601 S**
(45) Date of Patent: ** Feb. 18, 2025

(54) **STORAGE BATTERY**

(71) Applicant: **TOYOTA JIDOSHA KABUSHIKI KAISHA**, Toyota (JP)

(72) Inventors: **Toshio Uchiyama**, Toyota (JP); **Masateru Nakamura**, Ichinomiya (JP); **Takashi Murata**, Kasugai (JP); **Kazuki Kubo**, Toyota (JP); **Masahiro Misu**, Nisshin (JP); **Chihiro Onuma**, Nagoya (JP)

(73) Assignee: **TOYOTA JIDOSHA KABUSHIKI KAISHA**, Toyota (JP)

(**) Term: **15 Years**

(21) Appl. No.: **29/860,566**

(22) Filed: **Nov. 21, 2022**

(30) **Foreign Application Priority Data**

May 23, 2022 (JP) ..... 2022-010988 D

(51) LOC (15) Cl. **13-02**

(52) U.S. Cl.

USPC **D13/103**

CLAIM

The ornamental design for a storage battery as shown and described.

DESCRIPTION

FIG. 1 is a perspective view of a storage battery showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines and the masked portions within illustrate structure or features which form no part of the claimed design.

1 Claim, 7 Drawing Sheets
